UNITED STATES PATENT OFFICE.

ROBERT ÉMILE MARIE PÉNOT, OF LA SAULIAIE PRES BETZ LE CHATEAU, FRANCE.

AUTOMATIC PRINTING TELEGRAPH.

Application filed December 5, 1923, Serial No. 678,646, and in France December 14, 1922.

The invention relates to apparatus for automatically recording electrical signals in type-printed characters of the type which comprises a regulator sorting the signals according to their duration or nature, a distributor translating the signals into letters, and an apparatus for recording the translated signals. In the case of Morse signals and the like, for example, the regulator sorts the dots from the dashes.

It has already been proposed to provide recording apparatus in which the estimation of the length of the signals or spaces is effected by means of a sort of contactor or vibrator the period of vibration of which is very small relatively to the length of the signal or space to be estimated, the contactor being further combined with a number of relays to actuate a commutator for the letters. The latter apparatus is formed by means of electro-magnets into a certain number so as to be able to form all of the possible combinations of signals.

The apparatus of the present invention is differentiated from those previously known in that the members are considerably simplified.

To estimate the length of the signals or the spaces between signals the apparatus of the present invention comprises a mechanical regulator operated electrically by the impulses of received current, a distributor analogous to the known commutator for the letters but with the advantage of utilizing only a minimum number of electro-magnets, the said distributor comprising several groups of oscillating members each group consisting of two such members each actuated by a corresponding electro-magnet energized by currents from the regulator, such currents for one electro-magnet corresponding to dot received impulses and for the other electro-magnet to dash received impulses and a type writing machine associated with the distributor with its characters arranged circularly and operated under the control of circuits closed by the distributor.

This apparatus is such that it allows the translation and recording of Morse or the like signals at all speeds more especially for wireless telegraphy, but it is obvious that such apparatus can be arranged also for other line

telegraphy and the transmission of orders. The accompanying drawings represent one example showing the various parts forming the apparatus. In these drawings:

Figure 1 is a diagrammatic drawing of the regulator.

Figure 2 is a side view partly in section of the distributor.

Figure 3 is a view partly in plan and partly in transverse section of the distributor.

The two extremities of this figure are two plan views of the under part of the distributor the upper part being assumed to have been removed; while the central part is a transverse section of an element of the distributor on the line A—B of Fig. 2.

Figure 4 is a diagrammatic drawing of the connections of the distributor, and

Figure 5 a diagrammatic drawing of the electrically driven typewriter.

The regulator is constituted by the following elements:

An electric motor 1, coupled to a spindle X X' which carries a roller 2;

An anchored piece 3 pivoted at 4 and terminating in a pallet 5 situated in the magnetic field of two electric-magnets 6 and 7 which cause the roller 2, when there is an interval between signals, to enter into frictional engagement with a disk 8, and at each signal with a disk 9;

A relay 10 actuated by the device receiving the signals connected with terminals 11 and 12 controlling the electric-magnets 6 and 7;

A disc 8 turning with the shaft Y Y', on which it is mounted and constantly returned by a spiral spring 12 to its initial position by means of a projection 13 striking against a fixed spur 15. It is turned in the reverse direction by the friction of the roller 2, when the projection 13 is returned against a stop 14 and is there locked (in the position of rest) by means of a pawl 16 having a return spring 17 and operated by the anchor piece 3 which causes it to pivot about 18. The disc 8 involves in its movement two commutators 19 and 20 mounted on the shaft Y Y'. The commutator 19 connected with the ground wire of the apparatus co-operates with two brushes 21 and 22 and the commutator 20 also connected with the ground wire co-operates with a single brush 23.

100

At each interval between the signals, disc 8 turns through an angle in proportion to the period of friction of roller 2 and the angle is thus proportioned to the duration of the interval. Collector 19 closes the circuit by means of brushes 21 and 22 respectively on a terminal 24 for an interval of two letters (impression of the character selected and release of the distributor) and on terminal 25 for the interval between words (spacing). The collector 20 controls motor 1 whose circuit comprises in series a resistance 26 that may be shunted by a second resistance 27. This circuit is opened when the transmission is terminated.

Disc 9 turns with shaft Z Z' upon which it is mounted and is also returned by a spiral spring 28 to its initial position by means of a lug 29 striking against a fixed spur 30. In the reverse direction, by the friction of roller 2, the displacement of disc 9 is limited by another stop 31. This disc carries with its movement two collectors 32 and 33 mounted on shaft Z Z'. The collector 32 cooperates with two brushes 34 and 35 and the collector 33 with a single brush 36; these collectors have their conductive parts connected electrically. Disc 9 and therefore the collectors 32 and 33 turn with each signal at an angle in proportion to the time of friction of roller 2. For a short signal, collector 32 is only displaced slightly and is connected by means of its brush 34 on terminal 37 (terminal for short signals) a current coming from collector 33; for a long signal this collector turns at a greater angle and is connected by means of its brush 35 on terminal 38 (terminal for long signals) the current coming from collector 33.

An arrangement comprising a stop tooth 39, a collector 40 and clutch 41 the driving-plate of which is constantly driven by shaft X X'. This arrangement is mounted on a hollow shaft 42 turning on shaft X X', and may be locked in two diametrical positions by the anchored piece 3 which has for its purpose at each of its extremities a stop-spur 43 on which the cam tooth 39 locks. At the beginning of each signal this entire arrangement is liberated by the anchored piece 3 and makes a half revolution; the collector 40 grounded by being connected with the metallic mass of the apparatus places by means of its brush 44, resistance 27 in shunt across the resistance 26 and thus increases the speed of the motor 1, the current passing from the terminal 47 through motor 1, resistance 27, brush 44, collector 40 to the ground and from terminal 47, through motor 1, resistance 26, brush 23, collector 20 to the ground. The collectors 19 and 20, during this operation, have been rotated to bring their conducting parts into contact with their respective brushes, as will be more fully set forth in describing the operation of the machine.

Once the signal is terminated this entire arrangement completes one revolution and the collector 40 closes by means of its brush 45, on the collector 33, a circuit connected by the collector 32 on the short signal terminal 37 or on the long signal terminal 38 according to the position of disc 9; the circuit passing from the distributor (Figs. 2 and 3) through terminal 37 (or 38), brush 34 (or 35), collector 33, brush 36, circuit breaker 46, brush 45, and collector 40 to the ground.

A contact breaker 46 connected between collectors 40 and 33 does not permit the passage between terminals 37 and 38 of any but limited current and of a constant value necessary to the regular functioning of the distributor.

The regulator thus constituted is supplied by an electric source the positive pole of which is connected with terminal 47 and the negative pole with the terminal 48 which is grounded on the metallic mass of the apparatus with the view of simplifying the connections. The collectors 40, 19 and 20, as has been previously indicated, are grounded in the same manner.

The distributor is essentially constituted of several groups of pivoting pieces having contacts that cooperate with fixed contacts and actuated successively by the regulator by means of electric-magnets so as to select the short and long signals.

Each group comprises two pivotal pieces corresponding respectively to the dots and dashes of the Morse alphabet. These pivotal pieces being alike it is sufficient to describe but one of them.

Each pivotal piece is formed essentially of a spindle 49 journaled in bearings 50. This spindle has fixed upon it two plates 51 upon which are fixed perpendicular to the axis spring pallets 52 with contacts, which, when the spindle 49 turns, come into contact with the fixed contacts 53 connected with the circuits of the different letters. Certain of the contacts, as 57, 58, 59 and 60, operate in an inverse manner, being disposed for this purpose so as to be in contact with corresponding fixed contacts 53 when spindle 49 is in a position of rest while they open the circuits necessary during the oscillation of the said spindle 49. This oscillation of spindle 49 is obtained by means of an electric-magnet 54 receiving its current from the regulator by means of the short signal terminal 37 and the long signal terminal 38 which are respectively connected with terminals 55 and 56 of the distributor.

Several groups of turning spindles thus arranged and operated constitute the distributor. The number of these groups may vary according to one's needs. In the embodiment of invention illustrated as an example in the accompanying drawings there are five groups.

The first group comprises two spindles 49 corresponding to the short and long signals which are designated, to avoid confusion, by 49^a (short) and 49^a (long), or by using two forms of the Morse code, by 49^a (•) and 49^a (–). The electric magnets controlling these spindles may similarly be indicated by 54^a (short) and 54^a (long) or by 54^a (•) and 54^a (–).

10 The second group is made up of the spindles 49^b (short) and 49^b (long) actuated by the electric magnet 54^b (short) and 54^b (long).

15 The third group is made up of the spindles 49^c (short) and 49^c (long) actuated by electric magnet 54^c (short) and 54^c (long).

20 The fourth, fifth, and other groups are also composed of similar elements that may be designated in a similar manner having as indices the letters e, d, f, etc.

25 A sixth 49^f has a particular function: it is actuated by both the short and the long signals, and permits the unblocking of the distributor when the transmission is not well made. The typewriter mentioned later, therefore leaves blanks for all letters that are illegible. This may occur for example when there is an error of transmission or when static disturbs the relays.

30 When the spindles 49^a of the first group are at rest, their respective contact-breaks 57, 58 and 59, 60 are closed. Similarly, when the spindles 49^b of the second group are at rest, their respective contact-breaks 61, 62, 35 63 and 64, 65, 66 are closed. Also the spindles 49^c of the third group, when at rest, close the contact-breaks 67, 68, 69 and 70, 71, 72, etc.

40 Each of the electric magnets 54, after having caused the corresponding spindles 49 to oscillate, automatically locks the said spindles in working position by means of an appropriate lock.

The distributor is returned to rest, after the transmission of each letter, by means of a contact-break 73 actuated by an electric magnet 74 which unlocks from their working position the pivoting spindles that had served for the selection of signals. The electric magnet 74 is put into circuit at the moment 50 desired by the regulator, and, for this purpose, the terminal 75 of the distributor is connected with terminal 24 of the regulator which corresponds to the intervals between the letters.

55 Similarly terminal 76 of the distributor is connected with terminal 25 of the regulator which corresponds to the intervals between the words (spacing).

60 And lastly the local source of the electric current is connected with terminals 77 (positive) and 78 (negative).

At the first signal received by the relay 10, the regulator sends to the first group of the distributor a current that passes through 65 the electro-magnet 54 controlling the spindle

of the signals corresponding to the signals received. This spindle therefore closes a first contact-break in each circuit of the letters, numbers, or signals beginning with the signal received. For example, if the first signal received is a short signal, the regulator will send to the first group of the said distributor a current which will traverse the electro-magnet 54^a (•) actuating the short signals spindle. At the second signal received by 70 the relay 10 the regulator sends a current to the second group of the distributor which then closes a second contact break in each circuit of the letters, numbers, or signals having as second signal the signal received and 80 breaks the circuit of the letters having but one signal.

If the regulator sends a third, fourth, and fifth signal, etc.—the distributor successively closes by its third, fourth, fifth groups etc.— 85 the third, fourth and fifth contact-breaks of the circuit of the letters, numbers or signals comprising the number of signals considered and having as third, fourth, or fifth signal the signal received. On the receipt of a supplementary signal sent by the regulator the distributor opens the circuit of the letters, numbers or signals of which all the contact-breaks are closed.

The operation of this distributor will be 95 better understood by the following description relating to the working of the apparatus as a whole, covered by the invention.

The typewriter is electrically controlled by the distributor hereinbefore mentioned, and 100 is diagrammatically constituted of the following parts.

A wheel 79 turning on a shaft 80 and having on its periphery characters 81, 82, 83 etc. which is constantly in contact with an inking 105 roller 84 and is coupled by a friction gear with an electric motor 85 that is constantly in motion.

A printing cylinder 86 which carries in its rotary movement a band of paper 87 and is 110 further adapted to be automatically projected at the desired moment against the wheel 79 so that each letter desired is printed on the band of paper 87.

A fixed cylinder 88 concentric with the characters wheel and having on its periphery a series of pins 89, 90, 91... moving in a radial direction and equal in number to that of the characters. These pins are depressed under the action of respective electro-magnets 89^a, 90^a, 91^a... receiving their current from terminals 92, 93, 94... which are connected with each of the circuits of the letters of the distributor. Under these conditions the latter sends a current into that one of the electro-magnets 89^a, 90^a, 91^a which corresponds with the letter selected, and the desired pin is thus depressed.

A carriage or arm 95 which is fixed on the shaft of the character wheel 79 and which, 120

therefore, in striking against the depressed pin renders said wheel 79 stationary and closes by means of the contact 96 the circuit of an electro-magnet 97 which controls the striking movement of the printing cylinder 86 against the desired character.

A stamping electro-magnet 97 the movable armature 98 of which is pivoted at 99 with a return spring 100, cooperates with a ratchet wheel 101 forming part of the printing cylinder 86, to project the latter against the characters wheel 79 which at the moment is presenting the letter which is to be printed. This electro-magnet, after the impression of the letter, is returned to its original position by means of a system of articulated rods (not shown in the drawings), the pin that had been depressed, the carriage 95 and the character wheel thus becoming free. Another system of articulated rods 102 serves to advance the ratchet wheel at each impression.

The typewriter is supplied by the local source of the installation connected to the terminals 103 (negative) and 104 (positive) and the typewriter and the distributor are electrically insulated from one another.

The local source is therefore connected individually to the three devices as follows:—

To the regulator through terminals 47 (positive) and 48 (negative).

To the distributor through terminals 77 (positive) and 78 (negative).

To the typewriter through terminals 104 (positive) and 103 (negative).

There are further three main operative circuits as will be more clearly described in the method of operation hereinafter. These consist briefly of:

(a) a circuit allowing operation on the spindle 49 comprising negative through commutator 40, brush 45, collector 33, commutator 32, brush 34, terminal 37 to 38, terminal 55 or 56, closed contacts on spindle 49 to operating magnet 54 positive terminal 77 of battery to negative 78.

(b) a locking circuit for the spindle 49 comprising terminal 77 (positive) electromagnet 54, contact on spindle 49 closed on its operation contact 73, to negative 78.

(c) a circuit allowing operation of the typewriter on selection of the letter signalled and comprising negative, commutator 19, brush 21, terminal 24, terminal 75, electro-magnet 74, closed contacts on locked spindles 49, one of electro-magnets 89^a, 90^a, 91^a, to positive terminal 104.

Operation of the machine.

In order to clearly explain the role of the three devices described above, which constitute the automatic register according to the invention, the working of the entire machine will be described below for the reception of a letter, for example the letter U, which is

transcribed in the Morse code by two short signals followed by a long, thus (• • -).

At the reception of the first short signal, the receiving arrangement connected with terminals 11 of the regulator actuates the relay 10 which opens the circuit of the electro-magnet 6 and closes the local current on electro-magnet 7. The latter draws towards it the pallet 5 of the anchored piece 3 which, in a movement towards the left unlocks disc 8 as well as the device formed by the cam tooth 39, the collector 40 and the clutch 41, causing roller 2 to come into frictional engagement with disc 9.

Disc 8 drawn by its spring 12 turns about its axis carrying with it collectors 19 and 20, striking in 15 in its original position. The collector 20 in its movement closes, by means of resistance 26, the circuit of motor 1 which is put into motion and carries with it the shaft X X'.

This causes the entire arrangement 39—40—41, having been carried on by the clutch 41 and being no longer held back by anchor 3 which had moved to the left, to turn one half revolution and strike spur 43 to the right of the anchor. In this movement the conductive part of the collector 40 passes under brush 44 and the resistance 26 is shunted by resistance 27. By the decrease of resistance in series with the motor, the latter receives an impulse regulated by a fly-wheel, not shown in the drawing.

The roller 2 carried by the shaft X X' turns disc 9, which, the signal having been short, is displaced but little leaving the conductive part of collector 32 in contact with the brush 34 connected with terminal 37 for short signals.

At the end of this first short signal the relay 10 sends the local current into electro-magnet 6 draws towards it the pallet 5 of anchor 3. This anchor being displaced towards the right again liberates the arrangement 39—40—41 which closes by means of the collector 40, the brush 45 and the collectors 33—32, on the terminal 37 of the short signals and allows a current to flow the limited duration and constant value of which is regulated by the contact-breaker 46.

The current from the terminal 37 enters 115 the distributor by means of the terminal 55, passes through the closed contact-breaks 59 and 57 and returns to the local source by means of the electro-magnet 54^a (short) of the first group of shafts of the distributor. 120 Under the action of electro-magnet 54^a (short) the shaft 49^a (short) oscillates and becomes locked in operative position by a current coming from terminal 77 of the local source, passing through the electro-magnet 125 54^a (•), the contact break 105 then closed and the contact breaker 73. In its movement the shaft 49^a (•) opens the contact-breaks

57 and 58 and the electro-magnets 54^a (•) and 54^a (-) become isolated from the regulator so that the following current coming from this regulator may act on the second 5 group of shafts of the distributor. Simultaneously the said shaft 49^a (•) closes by its movement a contact-break in the circuit of the letters, numbers or signals having as first signal a short signal.

10 The second signal, also being short, current is led to the regulator in a manner similar to the preceding, to the terminal 55 of the distributor. The current passes by the closed contact breaks 106, 65, 62 and returns to the 15 local source by the electro-magnet 54^b (•) of the second group of the distributor. Under the action of this electro-magnet the shaft 49^b (•) oscillates and becomes locked in a working position by a current coming 20 from the local source by the terminal 77, passing by the electro-magnet 54^b (•), the contact break 107 then closes and returns to the local source by the contact-breaker 73. Simultaneously, in its movement, the shaft 25 49^b (•) opens the contact-breaks 61, 62, 63 and thus automatically isolates itself from the regulator. It allows at the same time by the third group of spindles of the distributor, of the receipt of any further impulse of the 30 current coming from the regulator, closes a contact-break in the circuit of letters, numbers or signals having as second signal a short signal and breaks the circuit of letters having but one signal by the contact-breaks 35 63 (elimination of the letter e (•) which would have been printed if an interval had occurred).

At the reception of the long signal forming the third signal, the regulator acts in a manner similar to the foregoing but the roller 2 causes disc 9 to turn at a greater angle so that collector 32 shunts the current through the brush 35 connected with the terminal 38 for long signals. This current comes into 45 the distributor by the terminal 56, passes by the closed contact breaks 108, 109, 68, 71 and returns to the local source by way of the electro-magnet 54^c (-) for the third group of spindles of the distributor. Under the action of this electro-magnet the axis 49^c (-) oscillates and becomes locked in a working position by a current coming from the terminal 77 of the local source, passing by the electro-magnet 54^c (-) and the closed contact-break 110 and returning to the local source by the contact-breaker 73.

This axis 49^c (-) in locking itself closes a contact-break in the circuit of the letters, numbers or signals having as third signal 60 a long signal, isolates itself from the regulator and opens the circuit of letters having but two signals (elimination of the letter i (••)).

The three signals being thus selected on 65 the distributor a stop is produced that cor-

responds to the interval between two letters. During this rest the roller 2 causes the disc 8 to turn at a greater angle than that for the short interval that separates two signals of the same letter, as a result of which the commutator 19 comes into contact, towards the end of the interval with the brush 21 suitably arranged for this purpose. The local current is therefore led from the regulator through the terminal 24 and enters the distributor by the terminal 75. There it traverses the electro-magnet 74 and passes through the contact breaks 111, 112, 113, 114 and 115 closed by the three axes blocked in a working position, to arrive at the terminal 75 of the distributor corresponding to the letter U. Thence the current passes through that one of the electro-magnets 89^a, 90^a, 91^a . . . of the typewriter corresponding to the letter U. This current depresses the corresponding one of the pins 89, 90, 91 and opens by the contact breaker 78 the blocking circuit of the three shafts of the distributor that had served for the selection of the letter received. The apparatus has thus returned to rest, ready to select the signals that follow.

During the reception of the following signals, the carriage 95 of the typewriter is stopped by the pin forced down on the letter U; the contact 96 is then automatically closed actuating the electro-magnet 97 that controls the striking movement of the printing cylinder 86 against the characters wheel and the letter U is thus printed on the paper band 87.

The roller 2 of the regulator then continues to carry forward the disc 8.

The commutator 19 by means of the brush 22 then closes the circuit on the terminal 25.

Current is led to the terminal 76, comes into 105 116 and passes through closed circuit by traversing an electro-magnet of the typewriter corresponding to a blank. There is thus formed on the band an interval analogous to that which is placed at the end of a word. The disc 8 of the regulator still continues to revolve until it is finally blocked by its retaining pawl 16. The commutator 20 then breaks the circuit of the motor 1 of the 110 regulator as well as that of the motor 85 of the typewriter.

The apparatus has thus automatically returned to rest.

This apparatus is applicable to all transmissions of Morse signals received either by wire or by wireless.

The printing process may also be different from that hereinbefore described. For example, for long messages, one may print on 125 a drum drawn forward with a helicoidal movement, and having on its surface a sheet of paper.

In general, the details of the arrangements of the apparatus may be modified without 130

thereby departing from the scope of this invention.

What I claim as my invention and desire to secure by Letters Patent is:—

- 5 1. An automatic telegraph system for recording grouped dot and dash signals in type printed characters comprising an electrically-operated printing typewriter, a plurality of electromagnets associated therewith
- 10 for controlling the printing of the characters thereof, distributing means including groups of pivoted contact members adapted to control the circuits of said electro-magnets, electrically actuated means cooperating with said members, and regulating means selectively controlling said last-named means and including selector switches, a pair of oscillating disks operatively connected to said switches, means for oscillating said disks, a
- 15 pair of electro-magnets one of which is adapted to be energized by the received signals, the other of which is adapted to be energized only during the intervals between signals, means associated with said pair of magnets for controlling the disk oscillating means whereby to cause said disks to oscillate respectively in response to signals and to the intervals between signals and establish a circuit through its selector switches and pre-determined contact members of the distributing means and energize the electro-magnet in the typewriter controlling the character corresponding to the received signals.
- 20 2. An automatic telegraph for printing grouped dot and dash signals comprising means separating dot signals from dash signals, distributing means connected to said separating means including groups of pivoted contact members adapted to contact with corresponding fixed contact members, and electrically actuated selecting means cooperating with said members, an electrically operated printing mechanism, and a plurality of electromagnets associated therewith for controlling the operation of said mechanism, the circuits of said electromagnets being controlled by said contacts, said separating means comprising selector switches, a pair of oscillating disks operatively connected to said switches, means for oscillating said disks, a pair of electromagnets one of which is adapted to be energized by the received signals, the other of which is adapted to be energized only during the intervals between signals, means associated with said pair of magnets for controlling the disk oscillating means whereby to cause said disk to oscillate respectively in response to signals and to the intervals between signals and establish a circuit through its selector switches and pre-determined contact members of the distributing means and energize the electromagnet in the typewriter controlling the character corresponding to the received signals.
- 25 3. In an automatic printing telegraph, a normally rotating wheel having type characters positioned around its periphery, a stop member fixed to the axis of said wheel and projecting outwardly from said axis, a normally open switch on the outer end of said stop member, a plurality of electromagnets disposed in fixed positions around the circumference of said wheel, radial pins adapted to be moved by said magnets into the path of said switch to thereby stop said wheel and close said switch, a printing electromagnet controlled by said switch, a printing cylinder normally slightly spaced from the periphery of said wheel, and means actuated by said printing magnet to move said cylinder into contact with the periphery of said wheel.
- 30 4. In an automatic printing telegraph, a normally rotating wheel having type characters positioned around its periphery, a stop member fixed to the axis of said wheel and projecting outwardly from said axis, a normally open switch on the outer end of said stop member, a plurality of electromagnets disposed in fixed positions around the circumference of said wheel, a fixed cylinder surrounding said wheel, radial pins slidably mounted in said cylinder and adapted to be moved by said magnets into the path of said switch to thereby stop said wheel and close said switch, a printing electromagnet controlled by said switch, a printing member mounted adjacent the periphery of said wheel, and means actuated by said printing magnet to move said printing member into contact with said characters.
- 35 5. In an automatic printing telegraph, a wheel having type characters positioned around its periphery, means for rotating said wheel, a stop member mounted in fixed relation to said wheel, a switch carried by said stop member, resilient means for normally holding said switch open, a hollow fixed cylinder surrounding said wheel, electromagnets mounted on said cylinder, means for causing dot-and-dash impulses to selectively energize said magnets, radial pins mounted in said cylinder and adapted to be moved by said magnets into the path of said switch to thereby stop said wheel and close said switch, a printing electromagnet controlled by said switch, a printing member mounted adjacent the periphery of said wheel, and means actuated by said printing electromagnet to move said printing member into contact with said characters.
- 40 6. In a distributing apparatus for a printing telegraph, a pair of spring-actuated oscillating disks, a pivoted anchor piece adjacent said disks and having at its one end a pallet and at its other end two opposed stop members, a pair of opposed electromagnets adapted to be energized respectively

when a signal is received and when an interval occurs between signals and adapted to actuate said pallet, a hollow shaft, a continuously rotating spindle releasably connected to said shaft, a cam mounted on said shaft for alternative cooperation with said stop members for locking and releasing said shaft,

and a friction roller mounted on said shaft adjacent said disks and adapted to contact selectively with the peripheries of said disks to rotate the same according to the position of the pallet.

In testimony whereof I affix my signature.
ROBERT ÉMILE MARIE PÉNOT.
